(57) **CLAIM**

The ornamental design for a body fat analyzer, as shown and
described.

DESCRIPTION

FIG. 1 is a front elevational view of our new design;

FIG. 2 is a rear elevation view thereof;

FIG. 3 is a top plan view thereof;

FIG. 4 is a bottom plan view thereof;

FIG. 5 is a left side view thereof;

FIG. 6 is a right side view thereof; and,

FIG. 7 is a perspective view thereof.

The ornamental design which is claimed is shown in solid
lines in the drawings. The broken lines in the drawings are
for illustrative purposes only and form no part of the claimed
design.
